DRAWING FIXTURE

James Dorsey Leffel, Newport, R. I., assignor to Remington Rand Inc., Buffalo, N. Y., a corporation of Delaware

Original application July 22, 1941, Serial No. 403,522. Divided and this application June 18, 1942, Serial No. 447,541

2 Claims. (Cl. 33—80)

This invention relates to a straight edge for a drawing fixture and the like.

This application is a division of application Serial No. 403,522, filed July 22, 1941.

The invention provides a drawing fixture or scope having a sheet supporting plate carried by a suitable frame formed to slidably mount a straight edge for sliding movement thereon and so arranged that it may be resiliently and slidably retained in position for slidable movement along the sides or the ends of the frame.

The straight edge of this invention provides a pair of guide members thereon, one of which is detachably retained in any one of a plurality of adjusted positions for resiliently retaining the straight edge on a drawing board fixture or the like for convenient sliding movement thereon during use.

In the drawing:

Fig. 1 shows a plan view of a frame having the straight edge applied thereto.

Fig. 2 is an enlarged cross section taken on line 2—2 of Fig. 1, having portions broken away, the guide member being in clamped position.

Fig. 3 is a bottom plan view enlarged, showing the structure of the guide member.

Fig. 4 is a side elevation of a portion of the straight edge and the guide member with portions broken away and shown in cross section, the parts of the guide member being in non-clamping position.

Fig. 5 shows the parts of the adjustable guide member in perspective in disassembled relation.

A frame 1 of rectangular form is provided for use in connection with the straight edge provided by this invention. This frame may be the frame of a drawing fixture for cutting stencils as shown in the aforementioned application, or a drawing board and the like. The frame is preferably provided with a flange 2 on its margin or other equivalent structure.

This straight edge includes an elongated strip 3 having a cross member 4 secured on one end and provided with a laterally extending guide flange 5 perpendicular to strip 3. The free edge of guide flange 5 is formed with a supplemental guide flange 6 extending toward the opposite end of strip 3 for the purpose of engaging the under side portion of the projecting edge or flange 2 of frame member 1 outside of the depending flange 1' of the frame member.

This provides a structure for slidably guiding one end of straight edge strip 3 along one side or end of frame 1 at the same time preventing

it from slipping off of the frame in the normal use of the straight edge.

The opposite end of strip 3 is slotted at 7 and formed with an upper serrated or transversely grooved face on opposite sides of the slot indicated at 8. A guide member 9 is formed of a U-shaped strip having the legs formed with inwardly extending slots on opposite side edges in aligned relation to receive the portions of strip 3 at opposite sides of slot 7 in slidable relation. The central section of guide member 9 is indicated at 10 and is located above or on top of straight edge strip 3 while the free ends of the legs extend below the strip in the manner illustrated in Figs. 2 and 3. One of the leg portions carries a resilient guide spring 11 formed to have the ends slidably engage the outside surface of depending flanges 1'. A spring pressed latch member 12 is fulcrumed in the central portion 13 of guide member 9 on top of strip 3 for movement between two positions, one of which is a locking position and the other a release position.

In the locking position spring pressed latch 12 has an end portion 14 that engages in the serrations or corrugations 8 on strip 3 in a position slightly inclined to a plane perpendicular to strip 3. In this position the laterally extending handle portion will engage one end of the top of said central portion 10 in the manner shown in Fig. 2 while a resilient operating spring 15 extending through a slot in end portion 14 will tend to retain the latch in this position because end portion 14 has passed the dead center position. In this position of end portion 14, it is wedged between central portion 13 and strip 3 for retaining member 9 in adjusted position to cooperate with cross member 4 to slidably mount the straight edge for parallel movement on frame 1. A retaining member 17 is mounted on and extends across the slotted end of strip 3 for retaining guide member 9 on the strip.

Whenever it is desired to use the straight edge to extend in a right angular direction from that illustrated in Fig. 1, this can be done by releasing latch member 12 through operating the handle on the end thereof so as to move end portion 14 about its fulcrum past the dead center position where spring 15 will move it out of engagement with the corrugated face 8 of strip 3 Fig. 4. This guide member may then be slidably moved lengthwise of strip 3 so that the straight edge construction may be disengaged from the frame as shown in Fig. 1 and applied across said frame with the cross head and guide mem-

ber positioned to retain and guide the straight edge for sliding movement.

The straight edge construction also provides a construction that can be placed upon the frame to extend either between the sides or the ends as desired and in which the guide member carried thereon can be adjusted to the distance between the sides or the ends in such a relation that the straight edge will be accurately and efficiently guided for sliding movement on the frame. The resiliency of guide spring 11 aids in retaining the straight edge in squared relation on frame 1 for easy sliding movement.

With this straight edge construction having the two guide members with one adjustable lengthwise of the straight edge, a construction is provided that will be efficiently guided on a stencil cutting scope and also on a drawing board for ready adjustment. This adds considerable convenience to a device of this character over the usual T-square because parallel movement over a drawing board and scope is facilitated by the guide members and the adjustable mounting of one on the straight edge provides for use of the straight edge on different sizes of boards and scopes in a convenient manner.

With this straight edge construction having the two guide members with one adjustable lengthwise of the straight edge, a construction is provided that will be efficiently guided on a stencil cutting scope and also on a drawing board for ready adjustment. This adds considerable convenience to a device of this character over the usual T-square because parallel movement over a drawing board and scope is facilitated by the guide members and the adjustable mounting of one on the straight edge provides for use of the straight edge on different sizes of boards and scopes in a convenient manner.

The invention claimed is:

1. A straight edge, comprising a strip member, a cross member mounted on one end of said strip member having guide means thereon perpendicular to said strip member, the opposite end of said strip member being formed with a longitudinal slot, a guide member slidably on said strip member having portions extending through said slot, said guide member having parts on opposite sides of said strip for engaging opposite faces thereof, and a latch member pivotally mounted on said guide member for movement into released position disengaged from said strip member and into latching position engaging said strip member and cooperating therewith to retain said guide member in adjusted position on said strip member,

said guide member having guide portions thereon in parallel opposed relation to the guide portions on said cross member for cooperation therewith in guiding said strip member at opposite sides of a supporting flange.

2. A straight edge, comprising a strip member, a cross member mounted on one end of said strip member and having a guide portion extending perpendicular to said strip portion, the opposite end of said strip member having a central longitudinal slot formed therein and a serrated face on one surface of said strip member adjacent to said slot, a guide member having a U-shaped strip formed with legs extending through said slot in said strip member and having slots formed in each leg for slidably receiving the portions of said strip member at opposite sides of said legs in slidable relation therein for slidably mounting said guide member on said strip member, the central portion of said guide member between said legs extending on the side of said strip member having said serrations, and a latch member formed of a piece of strip material having a portion extending on the side of said strip member having said serrations and a latch member formed of a piece of strip material having a portion extending between the central part of said U-shaped guide member and the corrugated face of said strip member and a handle portion extending laterally therefrom through an opening in the central portion of said guide member for manual operation to move said latch member between operative and inoperative positions, and resilient means for operating said latch member in opposite directions at either side of a dead center position to retain said latch member in latching position extending perpendicular between the central portion of said guide member and said strip member with the end engaging said strip member and said strip member with one end engaging in the serrations on the face of said strip member for latching said guide member on said strip member against movement, said resilient means retaining said latch member in inoperative position when moved the opposite side of the dead center position for disengagement of said latch member from said serrations in said strip member thereby providing for the sliding movement of said guide member longitudinally of said strip member, and guide portions on said guide member in parallel opposed relation to the guide portions on said cross members for cooperation of the guide members for parallel movement along opposite sides of a suitable frame.

JAMES DORSEY LEPPEL.
